A. B. Elpham,
Attorney.

UNITED STATES PATENT OFFICE

WALTER E. COPITHORN, OF NATICK, MASSACHUSETTS

SMOKER'S PIPE

Application filed May 27, 1927. Serial No. 194,646.

This invention has for its objects the construction of a pipe for smoking tobacco wherein the nicotine shall be practically wholly eliminated from the smoke on its way 5 to the user's mouth; and for keeping the exterior of the pipe comparatively cool.

To these ends, I have devised the construction hereinafter set forth and illustrated in the drawings forming a part of this specification, and in which Figure 1 is a side sectional view of a pipe embodying one form of my invention. Figure 2 is a horizontal section of the same on the line 2—2 in Figure 1. Figure 3 is a side sectional view of another form 15 of the invention.

The construction illustrated in Figs. 1 and 2 is in two parts, the bowl 1 and the body 2. The body has a cistern 3 into which the bowl descends, and an annular chamber 4 in its 20 wall into which the pipe stem 5 opens. The upper part of the bowl 1 is radially enlarged, as at 6, and threaded to screw into the upper end of the inner wall 7 by which the annular chamber 4 is inwardly bounded; and the 25 bowl is further provided with a flange or cap 9 enclosing the entire wall of the body 2. Below the shoulder 6, the bowl is spaced from the wall 7 and also from the floor of the cistern 3; and is provided with an opening 30 through the bottom, as at 10, for the passage of the smoke and vapors from the burning tobacco down into the cistern 3.

The oil of nicotine dripping through the opening 10 collects in the cistern, but the smoke rises up between the exterior of the bowl 1 and the wall or partition 7, until it reaches and passes through a hole 11 in the wall 7 into the annular chamber 4. To reach the pipe stem 5, which opens from the opposite side of the body 2, the smoke must move half-way about the wall 7; and not only so, but it must first enter the annular tube 12 through an opening 13, and traverse the 45 same until it can find its exit through an opposite hole 14 to permit it to reach the pipe stem.

I prefer to make the tube 12 of some inexpensive and more or less fibrous material similar to blotting paper, in order that it may ab-

sorb any remaining nicotine precipitated therein.

Thus disposed, three different places are provided for the collection of the nicotine; first, the cistern 3; the bottom of the chamber 4, and the annular tube 12; thus making sure that practically none of the nicotine can reach the mouth of the smoker.

For ensuring that the outer surface of the pipe shall be kept from becoming uncomfortably hot, I provide the outer wall of the body 1 with a multiplicity of vertical passages 15 reaching entirely through from the bottom and up through the flange 9. To make sure that the passages through the flange shall 65 communicate with those in the body, an annular groove 16 is formed either in the flange or in the body, but preferably in the latter, cutting into the ends of the passages 15.

In the construction shown in Fig. 3, the pipe is made in three parts, the cistern 20 being separable from the body 21 and internally threaded at 22. The bowl 23 is provided with a radially projecting flange 24 threaded to mesh with the threads 22, and by means of which it is held in place with its top flange 25 seated upon the body 21. Intermediate of the top and bottom of the bowl are two spiral flanges 26 adapted to receive the smoke at one point and to deliver it to the stem 28 at a diametrically opposite point.

To enable the products of combustion to reach the cistern 20 from within the bowl, the floor of the latter is given a hole 27, preferably near one side and sloping farther from the center at its lower end to present the products close to the wall of the cistern. A lip 29 is also provided for the lower end of the hole to ensure against any liquid adhering to the under surface of the bowl and 90 creeping along the same.

Up through the flange 24 diametrically opposite the hole 27 is a passage 30, whereby the smoke from the bowl passes downward through the hole 27, across the cistern, and up through the hole 30 into the lower portion of the space about the bowl, and thence through the space between the spiral flanges 26 to the pipe stem; thus ensuring that no nicotine can reach the mouth of the smoker. 100

After suitable intervals of use, the pipe is to be taken apart and the accumulations of nicotine and other products of the consumed tobacco emptied out from the parts.

5 As shown in the drawings, the flat contacting portions of the pipe are tongued and grooved, as at 32, in order to ensure against leakage of the smoke thereat. In Fig. 1, this is shown for the flange 9, but in Fig. 3, the 10 same feature is exhibited both in the flange and in the removable cistern portion 20.

What I claim as my invention is:

1. A smoker's pipe comprising, in combination, a stem portion, a body portion having a bowl therein, a cistern removable from said body, the lower portion of said bowl extending to said cistern and having a restricted outlet thereto, the walls of said body and bowl being spaced apart to provide a chamber between, a transverse partition between said chamber and said cistern provided with a restricted outlet therethrough, said pipe stem having a passage therein communicating with said chamber at or near the top 25 thereof.

2. A smoker's pipe comprising, in combination, a stem portion, a body portion having a bowl therein, a cistern removable from said body, the lower portion of said bowl 30 being provided with a restricted outlet running directly to said cistern, the walls of said body and bowl being spaced apart whereby a chamber is provided between them, a partition between said chamber and said cistern provided with an outlet therethrough whereby smoke may pass from said cistern 35 to said chamber, said pipe stem being provided with a passage communicating with said chamber.

40 3. A smoker's pipe comprising, in combination, a body portion having a stem and a bowl set into said body in spaced relation to the exterior wall thereof, a cistern below said body and detachably associated therewith, 45 said body being provided with a plurality of apertures through its exterior wall, said cistern being provided with a plurality of apertures through its wall, said pipe being provided with a passage in a plane transversely 50 of said apertures between said body wall and said cistern wall thereby insuring communication between said apertures in said body and cistern walls when said cistern and body are assembled.

55 4. A smoker's pipe in which there is a body, a stem, and a cistern attachable to and detachable from the lower part of said body, said cistern having apertures extending upwardly therethrough, said body having apertures extending upwardly therethrough intended for communication with the first said apertures whereby air is permitted to pass from below the bottom of said cistern to the top of said body, said pipe having a channel 60 formed at the union of said cistern and said

body for insuring communication between said apertures and a consequent open line of circulation at different points around the wall of the combined body and cistern.

In testimony that I claim the foregoing invention, I have hereunto set my hand this 25th day of May, 1927.
